Primary Examiner — Mimosa De(74) *Attorney, Agent, or Firm* — Greg M. Popowitz; Assouline & Berlowe, P.A.(57) **CLAIM**

The ornamental design for an angular shower bench, as shown and described.

DESCRIPTION

FIG. 1 is a front perspective view of a shower bench, with one panel set at an angle.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is an isolated view of the angled panel at a first angular position.

FIG. 9 is an isolated view of the angled panel at a second angular position; and,

FIG. 10 is an isolated view of the angled panel at a third angular position.

The illustrative broken lines depict environmental subject matter that form no part of the claimed design.
